UNITED STATES PATENT OFFICE.

JOSEPH A. THOMAS, OF BIRMINGHAM, ALABAMA.

DESIGN FOR A TOBACCO-CAN.

53,386.

Specification for Design.

Patented May 27, 1919.

Application filed November 15, 1916. Serial No. 131,593. Term of patent 3½ years.

To all whom it may concern:

Be it known that I, JOSEPH A. THOMAS, a citizen of the United States, residing at Birmingham, in the county of Jefferson and State of Alabama, have invented a new, original, and ornamental Design for Tobacco-Cans, of which the following is a specification, reference being had to the accompanying drawing, forming a part thereof.

Figure 1 is a perspective view of a tobacco can, showing my new design; and Fig. 2 is a bottom plan view.

I claim:

The ornamental design for a tobacco can, as shown.

JOSEPH A. THOMAS.
